Process of Evaporating, Crystallizing and Refining
Saccharine Solutions and Producing Dry Refined Sugar
No. 242,216.

Patented May 31, 1881.

UNITED STATES PATENT OFFICE.

JAMES A. MORRELL, OF NEW YORK, N. Y., ASSIGNOR TO MORRELL SUGAR
EVAPORATOR COMPANY, OF SAME PLACE.

PROCESS OF EVAPORATING, CRYSTALLIZING, AND REFINING SACCHARINE SOLUTIONS AND PRODUCING DRY REFINED SUGAR.

SPECIFICATION forming part of Letters Patent No. 242,216, dated May 31, 1881.

Application filed November 4, 1880. (No model.)

To all whom it may concern:

Be it known that I, JAMES A. MORRELL, of the city, county, and State of New York, have invented an Improved Process of Evaporating, Crystallizing, and Refining Saccharine Solutions and Producing Dry Refined Sugar, of which the following is a specification.

On the 12th day of September, A. D. 1871, Letters Patent of the United States were issued to me, numbered 118,875, for an improved process for the manufacture of sugar by the use of currents of heated and rarefied air surcharged with electricity, passed through the cane-juice or other designated liquor or substance while undergoing evaporation; and also on the 22d day of July, 1873, Letters Patent of the United States were issued to me, numbered 141,087, for improvements in the process of manufacturing sugar by passing induced currents of electricity through the saccharine solutions, whether accompanied by atmospheric currents or not; and also on the 2d of September, 1873, Letters Patent were issued to me, numbered 142,498, for the process of facilitating graduation by currents of electricity, and I am aware that heated air has been driven through sugar for the purpose of purging or drying the same.

In the practical operation of these processes I have discovered that by deoxidizing atmospheric air, producing a nitrogenous vapor, and applying it to the saccharine solutions at the several stages of the process of sugar manufacture, as hereinafter designated and described, I am enabled to preserve and crystallize in the sugar all of the saccharine properties of the cane-juice, leaving no residue or waste in the form of glucose or molasses.

To enable persons skilled in the art to operate my improvement in the art of sugar-manufacture, I will now describe one form of apparatus by which my improvement may be operated, referring to the drawings by letters of reference; but in this application I do not desire to limit my process to any particular form of apparatus, as I may make that the subject of a future application.

I employ a volume of compressed air driven by a double-acting air-pump, A, which forces the air into a receiver, B, provided with a

weighted valve, B', by means of which the pressure and current of air may be regulated by the operator to suit the varying necessities of the process of manufacture. The air passes from this receiver, by means of a pipe, B², into a coil, C, which is located and inclosed in the heated portion of a reverberatory furnace, D, where it is heated to a proper degree and then allowed to escape from the coils of this pipe into a receiver, D', which is located inside of the coil and heating-furnace at the bottom of a 1 under a series of perforated plates, D², or racks, having upon them copper and iron and such diverse metals as may be deemed proper to be used, such metals lying loosely or being coiled, so that the heated air may be driven through and around them. The compressed air is thus heated, deoxidized, electrized, and converted into a heated deoxidized and electrized aeriform fluid. At the summit of this receiver an exit-pipe, C', is located, which, taking several coils C² downward around the receiver in the heated portion of the furnace, passes out through its walls, connecting with pipe B³. Its contained gas or heated aeriform fluid, before described, is now ready to be applied to the various stages of the manufacture of sugar, as hereinafter more fully described.

Coils of copper D³ may be inserted in the furnace and conducting-pipes, which will greatly add to the electrizing of the heated aeriform fluid before described.

In crushing the cane to extract or present the cane-juice there is also extracted or presented and commingled with the cane-juice a white flooky albuminous substance which comes from the joints of the cane. In the old methods of manufacturing sugar this albuminous substance entangled or embraced with it a large percentage of the saccharine properties or matter of the cane-juice and prevented the formation of sugar by preventing crystallization, thereby producing in sugar-making a large refuse in the form of molasses and sirups.

My first purpose in the art of sugar manufacture is to avoid this great waste, which I fully accomplish in the following manner; but in the process of accomplishing this result I have discovered that I also accomplish a pri-

mal and very important result, which I will first set forth.

After the cane-juice has been suitably strained I place it in an elevated vat, E, which 5 has an opening, E', in its bottom, in which a pipe, E², is attached. I incase this pipe in a closed steam-jacket, E³, into which I admit steam by a pipe, E⁴, for the purpose of heating the contained juice to a high degree of 10 temperature, and to contribute more surely and economically to this result I insert a round wooden shaft, F, into the pipe containing the juice centrally, which, forcing the juice from the center of the pipe, presents it in a thin tubular body exposed to the pipe E² within the steam-jacket. The effect of this heat, as thus applied direct to the entire mass of the contained cane-juice, is to coagulate the albuminous substance of the juice, and entirely destroy 15 the fungous spores in the juice, which develop fermentation. When this feature of the process is properly applied granulation by atmospheric evaporation will occur without fermentation.

25 In my apparatus as devised and constructed by me, by means of properly jointed pipes F' I return the cane-juice, yet in a highly-heated state, from the steam-jacket last described, in a vertically-upward direction into a disintegrating-tank G, the conducting-pipe terminating by means of an angle or goose-neck, F², in a horizontal position. The end of the pipe is so flattened as to present an opening, F³, which vertically is very narrow and gradually increases in section rearward from the opening F³, and which opening is longitudinally long or wide and gradually decreases in section rearward from the opening F³. By this device I provide for the delivery of the heated cane-40 juice from this pipe in a vertically thin and horizontally broad film or sheet. Placed over and incasing the flattened opening of this pipe is a proper disintegrating-tank, G, large, deep, and covered, and provided with an opening 45 protected by a pipe, G'; for the escape of the gases which may seek an escape therefrom. Just below the goose-neck in this vertical conducting-pipe F', which contains and conducts the highly-heated cane-juice to this last-mentioned tank, I form a connection of a pipe, B⁴, containing the highly-heated aeriform fluid, which is, as I have before stated, under a regulated pressure. Proper stop-cocks A' A² A³ A⁴ are inserted in these pipes, by which the flow 55 of cane-juice, steam, or heated aeriform fluid may be regulated or suspended.

When all of the above-mentioned stop-cocks are properly opened the effect is as follows: The cane-juice is quickly and intensely heated 60 in the steam-jacket E³, the albuminous substances therein are coagulated, and the fungous spores are destroyed. The juice flows to the flattened opening F³ of the pipe F', and the highly-heated aeriform fluid under great 65 pressure and with great force disintegrates the coagulated masses of albuminous substance without its embracing any of the saccharine

properties of the cane-juice, and at the same time producing evaporation, and thus, without loss of any of the valuable properties of the cane-juice, the albuminous substance is liberated from the saccharine properties.

The object of liberating the albuminous substance, as above described, is to prevent the formation of molasses, or what, in plantation terms, is called "glucose."

The disintegrating-tank G is connected with a receiving-tank, G², by proper pipes G³, into which the cane-juice is permitted to flow and rest until the coagulated and disintegrated albuminous substance has become fully precipitated. A filter, G⁴, may be interposed in this pipe G³ to assist clarification.

At a proper place in the receiving tank above the sediment H, I attach a conducting-pipe, H', which extends downward and terminates in a coupling-piece, H², about one-half an inch in diameter. This coupling-piece enters one end of a pipe, H³, which is reduced to about one inch in diameter. This pipe may be some ten feet long, and at its other end is connected by a return-joint, H⁴, with a similar pipe, H⁵, of about the same length. These two pipes thus attached are placed in a steam-jacket, I, with their free ends extending out of and through the cap or cover of the same. The returned end of this pipe H⁵ is bent downward, as shown at I', into a deep tank, I². This tank is also covered and provided with an opening, I³. The entering end H⁶ is reduced to about three-fourths of an inch in diameter and connected by proper pipes B³ and B⁶, provided with stop-cocks K and K', with the main pipe leading from the furnace containing the heated aeriform fluid before described. The coupling-piece H² conducting the cane-juice is connected with the pipe H³ just immediately in front of the reduced connection H⁶ of the pipe B⁶.

The set of stop-cocks A', A², K, and K' being opened, the operation is as follows: The cane-juice from the receiving-tank G² flows into the entering end of the steam-jacketed pipe H³, the steam from the pipe I⁴ entering the steam-jacket I contributes to heating the juice, and the intensely-heated aeriform fluid, under great pressure, atomizes the juice, absorbing a great part of the oxygen, and converting the remaining water into steam, and drives all with great force and rapidity through the return-pipe H⁵ into the deep tank I², from which the steam and gases are permitted to freely escape, leaving the juice in the vat in a highly-heated and greatly-evaporated condition.

This process, when properly conducted, as above described, will reduce the cane-juice to a proper condition to be introduced into the granulating vacuum-pan. The vacuum-pan M is properly connected by conducting-pipes L, connecting it with the last-mentioned receiving-tank I² in such a manner that when the interposing stop-cocks L' and L² are opened the contents of the receiving-vat I² will flow into the vacuum-pan M. This vacuum-pan is of a spherical form, provided with a blast-draft

M^7 , coiled pipe M^2 for the introduction of steam for evaporating purposes, a bottom steam-jacket, M^3 , for the same purpose, and also a coil of perforated pipe, M^4 , which is connected with the main pipe B^3 , conducting the heated deoxidized and electrized aeriform fluid, hereinbefore mentioned, by pipe M^5 , provided with the stop-cock M^6 . In this vacuum-pan the mass is reduced to a proper consistency for sugar. When this consistency is reached the mass is dumped into a drying-receptacle, N , below. The bottom of this drying-receptacle is semi-cylindrical, and is provided with a steam-jacket, N' , for keeping up the heat of the mass contained in it. It is also provided with a large opening, N^2 , in its bottom, and by a large pipe, P , connected with a sugar-receptacle, P' , below, and also provided with a blast-draft, R^4 , to remove all steam and vapors which may be evolved in it.

Extending through the ends of the drying-receptacle, and on the line of the axis of its semi-cylindric bottom, is a tubular shaft, R , to which are connected tubular arms R' at proper intervals, upon which are connected series of tubular bars R^2 , all intercommunicating and perforated with small holes, and so connected, constructed, and arranged that as this tubular shaft is revolved, having first been placed by proper pipes B^5 and connections B^7 in connection with the main pipe B^3 , containing the heated deoxidized and electrized aeriform fluid, before described, the latter will continually escape through all of the openings in the arms and bars of this revolving shaft.

The operation and effect of this feature of the process is this: Motion being communicated to the shaft R , and the heated aeriform fluid, before mentioned, being turned on, the blast R^4 applied, and the steam introduced into the steam-jacket N' , the sugar is most completely crystallized, refined, and dried. When this has been conducted to a proper degree or extent the sugar is dumped through the large opening N^2 and pipe P , before described, into the sugar-receptacle P' . This sugar-receptacle is so constructed that it can be closed air-tight after the sugar has been placed in it. The beneficial results of this last-mentioned feature of my process is that by the sugar being placed in an air-tight receptacle, as it comes in a highly-heated state from the crystallizing and drying receptacle N , oxidation, discoloration, and deterioration are avoided while the sugar is cooling, after which, under proper conditions, when manufactured by my process, the sugar will preserve its properties and condition; but if this sugar, upon coming from this drying-receptacle N in a completely dried and highly-heated condition, be exposed to the air, it will absorb moisture and become somewhat deliquescent.

In the old methods the sugar comes from the drying devices in a highly deliquescent condition, and requires atmospheric evaporation and manipulation to prevent its becoming a hardened mass, and to complete the drying process

and insure drainage, which caused great deterioration and loss of the sugar as actually produced.

In my patent of September 12, 1871, No. 118,875, I described a process for driving currents of rarefied air impregnated or surcharged with electricity through cane-juice, sirup, &c., while undergoing evaporation. The improvement which is the subject of the present application is distinguished from that by the additional operation and feature of deoxidizing the air, as well as heating and electrizing it. Also, in my patent of July 22, 1873, No. 141,068, I described a process for introducing heated air into the body of the cane-juice to destroy the fungous spores which develop fermentation. In the present application I describe a process for introducing the heated air in such a manner as to atomize the cane-juice and disintegrate the coagulated albuminous substance therein contained.

By the proper employment of these several processes, or several features or stages of a process, in the manufacture of sugar I avoid the use of lime or any other substance for neutralizing purposes. I also avoid the use of blood or animal albumen for defecating purposes. I do not add to the cane-juice any drug or foreign substance in any stage of the manufacture of sugar or molasses, and by my process, as herein described, I am enabled to eliminate all foreign and deleterious substances which may be in the cane-juice, as first presented from the cane, without the loss of any of the saccharine properties of the juice. I avoid fermentation and the formation of glucose, with all of their attending losses. I provide a most economic and effectual system of evaporation. I produce a sugar, as a result, that is thoroughly crystallized, dried, and refined; and, finally, I avoid the great losses by drainage of the sugar, which are well known to be a large percentage of the whole amount as produced by the old systems.

I disclaim, in this case, any process in which a saccharine liquid is blown through an externally-heated tube or conduit into a vessel provided with a vent for the escape of vapors, and the apparatus therefor, as shown in the drawings and described in the specification.

Having thus described my process and one form of apparatus for operating it, what I claim as a new and useful improvement in the art of manufacturing sugar is—

1. The process of separating albumen from cane-juice and liberating the saccharine matter which consists in heating the juice and admitting to the flowing juice a current of heated aeriform fluid, and forcing the juice through a contracted opening, thus atomizing the liquid, evaporating the water, and disintegrating the albumen.

2. In the manufacture of sugar, after the evaporation of the cane-juice nearly to the point of granulation, the process of granulating the same which consists in forcing through the mass currents of heated deoxidized aeriform fluid.

3. In the manufacture of sugar, after evaporation of the cane-juice nearly to the point of granulation, the process of granulating the same which consists in forcing through the mass currents of heated deoxidized and electrized aeriform fluid.
4. In the manufacture of sugar, after the granulation of the saccharine mass nearly to the point of crystallization, the process of crystallizing and drying the sugar which consists in forcing through the mass currents of the heated aeriform fluid described, and simultaneously agitating the mass.
5. In the manufacture of sugar, after the granulation of the saccharine mass nearly to the point of crystallization, the process of crystallizing and drying the sugar which consists in forcing through the mass currents of heated and deoxidized aeriform fluid, and simultaneously agitating the mass.
6. In the manufacture of sugar, after the gran-

ulation of the saccharine mass nearly to the point of crystallization, the process of crystallizing and drying the sugar which consists in forcing through the mass currents of heated deoxidized and electrized aeriform fluid, and simultaneously agitating the mass.

7. In the manufacture of sugar in which the saccharine matter is heated with currents of heated deoxidized and electrized air, the process of preventing the sugar from oxidizing, discoloring, and becoming deliquescent which consists in placing the sugar in a closed receptacle for the purpose of cooling the mass.

In testimony that I claim the foregoing as my own I affix my signature in presence of two witnesses.

JAS. A. MORRELL.
